UNITED STATES PATENT OFFICE.

JOHN AUGUSTUS ENOS, OF PEABODY, MASSACHUSETTS.

TRANSCYCLE.

SPECIFICATION forming part of Letters Patent No. 311,112, dated January 20, 1885.

Application filed January 8, 1883. Renewed December 9, 1884. (No model.)

To all whom it may concern:

Be it known that I, JOHN A. ENOS, of Peabody, in the county of Essex and State of Massachusetts, have invented a new and useful Improvement in Transcycles; and I do hereby declare that the following is a full, clear, and exact description of the same, reference being had to the accompanying drawings, forming part of this specification, in which—

10 Figure 1 is a side elevation of my invention. Fig. 2 is an end or edge view. Fig. 3 is a top view of the saddle-frame. Fig. 4 is a cross-section of the rail and the flange of the wheel. Fig. 5 is a detail of one of the journal-bearings 15 of the wheel-shaft.

My invention is designed to provide a speedy and easy means of transportation, which I have styled the "Transeycle."

It consists of a single wheel mounted upon 20 an elevated track, combined with a seat and a treadle or driving mechanism, located beneath the point of support and connected to the wheel by a peculiar trussed frame extending up on one side of the rail, and also by a 25 gearing for transmitting the power generated below to the wheel above for the purpose of propelling the same on the track, all as hereinafter more fully described.

In the drawings, A represents vertical posts 30 or standards, having offsetting arms B fixed at right angles to the posts near the top, and strengthened by braces CC'. On the outer ends of these arms is supported a stringer or beam, D, upon which is laid the single rail E, the 35 whole forming an elevated single track. The general form of the rail in cross-section is right-angular, one of its flanges being its base, by which it is bolted to the stringer, and the other flange standing vertical, and being formed 40 with a round swell, a, (see Fig. 4,) at its upper edge. Upon this rail is arranged a large wheel, F, which is unlimited as to size, and in this respect is unlike the wheel of the ordinary bicycle, which is limited to the length required 45 by one's legs. In other respects this wheel is like the ordinary bicycle-wheel, being formed with radial spokes of steel wire and a grooved periphery, which groove fits around the part a of the rail. Projecting laterally from this 50 wheel is a shaft, G, fixed rigidly to the same, and carrying at its remote end a disk, b, and

wrist-pin c. Connecting this wheel and its shaft with the driving mechanism below is a light frame-work composed of a vertical pipe or hollow rod, H, and braces c c d e. At the 55 upper end of this frame are two boxes, f f, (see Figs. 2 and 5,) in which is journaled the wheel-shaft G. Near the lower end of the main frame is the horizontal saddle-frame I, (see Fig. 3,) which saddle-frame is bolted to 60 the main rod H and the braces c, and upon which is detachably clamped the saddle or seat J. At the extreme or lowest end of the main frame is another horizontal frame, K, carrying two bearings, g g, in which is journaled 65 the double-crank shaft L, carrying pedals i i. On one end of this crank-shaft is a disk, M, and wrist-pin j, to which latter is jointed the lower end of a braced or skeleton connecting- 70 rod, N, which at its upper end is jointed to the wrist-pin of the wheel-shaft. It will therefore be seen that when the operator is seated on the saddle his center of gravity will be approximately beneath the point of support of the wheel on the track, and the vertical position of the device will be perfectly maintained, and whenever power is applied 75 through his feet to the treadles the crank-shaft will be rotated and the power transferred to the wheel-shaft above through the connecting- 80 rod to cause a travel of the wheel over the track with its subjacent load.

The device as thus described forms a very light, easily-driven means of transportation, and one capable of great speed without danger 85 of being upset.

I do not confine myself to any particular means for driving the device, and instead of the treadle may employ any light motor. I may also, instead of using a connecting-rod 90 for transmitting power from the lower to the upper shaft, employ a shaft with bevel-wheels, a flexible shaft-coupling, a belt, or any other equivalent means for transmitting the motion. I may also make the connecting-rod to vibrate 95 about its center to cause its upper end to pass the dead-centers. This may be effected by a slot in the connecting-rod and a fixed pin on the frame passing through it, or by a pin on the connecting-rod and a slot in the frame. 100

I am aware of the fact that a basket has been suspended upon a flexible cable by a wheel,

and a belt provided for the rotation of said wheel, and I do not claim such arrangement.

My invention is distinctive in the peculiar construction of the light skeleton trussed frame connecting the wheel above to the seat and driving mechanism below, which frame is sufficiently light as not to materially affect the relation of the center of gravity of the rider to the point of support, and yet is sufficiently rigid by reason of its trussed or braced character as to permit the frame to extend wholly upon one side of the rider and the rail and still resist any tendency to bend.

Having thus described my invention, what I claim as new is—

1. The combination, with a supporting-wheel and a subjacent seat or saddle, of a light

rigid skeleton frame connecting the seat to the wheel upon one side of the same and trussed or braced substantially as described, and 20 means for driving said wheel, located at the lower end of the frame and connected to the wheel above, substantially as set forth.

2. The combination of the wheel F with rigid shaft G, the supporting-frame H c d e, 25 bearing offsetting saddle J, the double-crank shaft L, and the connecting-rod N, transmitting motion from the crank-shaft to the wheel-shaft, substantially as described.

JOHN AUGUSTUS ENOS.
